UNITED STATES PATENT OFFICE.

ARTHUR B. SEVERN, OF PITTSBURGH, PENNSYLVANIA, ASSIGNOR TO A. STUCKI, OF PITTSBURGH, PENNSYLVANIA.

ROLLER SIDE BEARING.

Application filed October 2, 1922. Serial No. 591,721.

To all whom it may concern:

Be it known that I, ARTHUR B. SEVERN, a citizen of the United States, and a resident of Pittsburgh, in the county of Allegheny 5 and State of Pennsylvania, have invented a new and useful Improvement in Roller Side Bearings, of which the following is a specification.

This invention relates to anti-friction side 10 bearings for railway cars and has for its objects the provision of a bearing of this type in which the roller is self-centering, in which the liability of the roller developing flat spots or recesses on its circumference, or the track upon which the roller runs becoming rough or recessed, thus interfering with the free travel of the rolling element, is prevented, and in which the roller gravitates to the center of its track under 15 its own weight immediately after contact between the upper bearing plate and the roller is broken, that is, as soon as the body of the car lifts sufficiently to break contact with the roller.

25 A special object is to provide a side bearing which obviates the necessity of using any special devices for moving the roller, either into operative or inoperative positions.

30 Another special object is to provide a side bearing having a free roller which will be positively retained in operative relation with the lower bearing surface and will not be displaced or lost regardless of the degree 35 of vertical clearance between the roller and upper bearing plate and at the same time will be hindered in its longitudinal movement upon its lower bearing surface by the minimum frictional resistance.

40 A further special object is to provide a bearing in which substantially the entire lower bearing surface will be exposed so as to render the same readily self-cleaning.

45 And it is still a further special object of the invention to provide an oscillating retaining frame for the anti-friction roller which is entirely mounted upon the exterior of and is supported by the base plate of the lower bearing surface, and in which said frame is so associated with the remaining 50 parts that the roller is prevented from con-

tacting the sides thereof during normal operation.

Further objects of the invention are to provide a side bearing of the character 55 named which will be light in weight yet sturdy and durable, which will be easy to manufacture and repair, which can be produced at a minimum cost, and which will function efficiently for the purposes intended. 60

In the accompanying drawings Fig. 1 is a plan view with the retaining frame in mid-position showing one embodiment of the invention; Fig. 2 a side view of the 65 bearing illustrated in Fig. 1, said view being partly in vertical section and partly in elevation; and Fig. 3 an end view partly in vertical section and partly in elevation, illustrating the method of mounting the oscillating retaining frame upon the base 70 plate.

The preferred embodiment of the invention comprises a base plate 1 provided with the apertured attaching ears or lugs 75 2 and 3 at its opposite ends, the base plate being suitably bolted or riveted to the truck bolster in the usual manner. Flanking the sides of the base plate are a pair of upstanding ribs or flanges 4, 5, from the exterior 80 surfaces of which extend the respective trunnions 6 and 7. The flanges 4 and 5 extend upwardly a short distance above the upper surface of the base plate 1, forming a recessed trough in which the lower bearing plate 8 is disposed, the bearing plate being rigidly secured in position upon the base plate 1 by means of suitable fastening 85 devices such as the rivets 9 and 10.

The upper surface of the lower bearing plate 8 is formed with a plane or flat intermediate portion 11 and the upwardly and outwardly inclined extremities 12, 13. The cylindrical anti-friction roller 14 is supported by the lower bearing plate, and normally rests freely thereupon, the inclined extremities 12 and 13 rendering the roller self-centering under the influence of gravity whenever the upper bearing plate 15 is out of contact therewith, during which time the 100 roller rests upon the intermediate portion 11 of the bearing plate 8. The upper bear-

ing plate 15 is attached to the bolster of the car body in the usual and well known way. The upstanding flanges 4 and 5 extend the full length of the bearing and project upwardly to such an extent as to embrace the sides of the roller 14, serving to prevent undue lateral displacement thereof. Pivottally mounted upon the trunnions 6 and 7 by means of the apertured bosses 16 and 17 is a retaining frame indicated as a whole by the reference character F, said bosses being formed at the lower extremities of a pair of longitudinal side members 18, 19 which are connected by the spaced-apart transverse frame members 20, 21. The height of the oscillating frame F is such that the roller 14 extends at all times slightly above the same, and the distance between the transverse bars or frame members 20, 21 is slightly less than the diameter of the roller, so as to prevent vertical movement of the roller to such extent as to become displaced or lost. The distance between the upstanding flanges 4 and 5 is slightly greater than the width of the roller 14 so as to permit the roller to freely move longitudinally upon the lower bearing plate, while the distance between the longitudinal side frame members 18, 19 is somewhat greater than the distance between the upstanding flanges. It is obvious that such construction will prevent the roller 14 coming into contact with the side members of the retaining frame during operation thereof, because the roller will contact either flange 4 or 5 before it has moved laterally a sufficient extent to be brought into contact with the side frame members. The inner upper surfaces of the transverse bars 20, 21 are somewhat curved as at 22 and 23 so as to contact the periphery of the roller throughout a substantial extent when the roller has been moved to an extreme position such as indicated by the dotted line showing at 24, and the side members of the retaining frame are provided with the openings or recesses 25, 26 for the purpose of reducing the weight thereof.

The operation of the device is as follows: The roller 14 normally rests upon the flat intermediate portion 11 of the lower bearing plate. Whenever the car body sways sufficiently the upper bearing plate 15 is brought into contact with the roller and any swiveling movement of the truck will cause the roller to ride up on the inclined end portions 12 or 13. As the body lifts, contact between the bearing plate 15 and the roller is broken, permitting the roller to gravitate under its own weight back to the flat central portion 11. The return of the roller occurs immediately upon the lifting of the body and without the use of any auxiliary mechanism or parts. This quick return due to the lack of all lost motion devices and the

free mounting of the roller is found to be of great practical importance, and with applicant's device is secured by a very simple construction.

Due to the fact that the flat central portion 11 is of appreciable length, the roller 14 will not always come to rest at the same point but at various points throughout its length and will rest upon various parts of its own periphery, thus assuring substantially uniform wear of both the bearing plate and the roller.

During the longitudinal movement of the roller upon the lower bearing plate, the same is prevented from being laterally displaced by means of the upstanding flanges 4 and 5, and is positively retained in operative position and prevented from being vertically displaced or lost by means of the retaining frame, said frame freely swinging about its pivotal connection furnished by the trunnions 6, 7, and the apertured bosses 16, 17.

The lower bearing surface is freely exposed and is unobstructed at the ends thereof so that any dirt or foreign substances deposited thereon will be readily discharged, rendering the bearing self-cleaning.

The bearing described is of simple construction, is economical to manufacture, easy to repair, is very durable and efficient in operation, is quickly responsive and self-centering, contains a minimum number of parts and is so constructed as to prevent accumulation of dirt or foreign substances upon the bearing surfaces.

I claim:

1. A side bearing for railway cars comprising a supporting base provided with a lower bearing surface, a free roller cooperating therewith, an oscillating retaining frame pivoted to the base surrounding the roller and rotatable about a fixed axis, the distance between the transverse bars of said frame being less than the diameter of the said roller.

2. A side bearing for railway cars comprising a supporting base provided with a lower bearing surface and upstanding flanges adjacent said bearing surface, an oscillating retaining frame pivoted to the base surrounding the roller and oscillating about a predetermined axis, the distance between the transverse bars of said frame being less than the diameter of the said roller.

3. A side bearing for railway cars comprising a supporting base provided with a lower bearing surface and upstanding flanges adjacent said bearing surface, trunnions projecting from the said flanges, an oscillating retaining frame pivoted to said trunnions, the distance between the transverse bars of said frame being less than the diameter of said roller.

4. A side bearing for railway cars com-

prising a supporting base provided with a lower bearing surface and upstanding flanges adjacent said bearing surface, trunnions projecting from the said flanges, an oscillating retaining frame pivoted to said trunnions, the distance between the transverse bars of said frame being less than the diameter of said roller, and the distance between the

longitudinal side bars of the frame being greater than the distance between said upstanding flanges. 10

In testimony whereof, I sign my name.

ARTHUR B. SEVERN.

Witness:

EDWIN O. JOHNS.
